[57] CLAIM

The ornamental design for a travel jewel case, as shown and described.

DESCRIPTION

FIG. 1 is a bottom, front, right perspective view of a travel jewel case showing my new design in closed position;

FIG. 2 is a perspective view thereof in open position;
FIG. 3 is a perspective view of a travel jewel case showing a second embodiment of my new design in open position.

The rear elevational view of both embodiments is plain and unornamented.
